UNITED STATES PATENT OFFICE.

CHARLES F. BROADBENT, OF BALTIMORE, MARYLAND.

SIGN.

1,143,168.

Specification of Letters Patent. Patented June 15, 1915.

Application filed August 28, 1914. Serial No. 859,010.

To all whom it may concern:

Be it known that I, CHARLES F. BROADBENT, a citizen of the United States, residing at Baltimore city, State of Maryland, 5 have invented certain new and useful Improvements in Signs, of which the following is a specification.

This invention relates to the manufacture of brilliant signs and has for its objects to 10 provide a sign of this character of improved construction.

In order that the construction and arrangement of the parts comprising the invention may be readily comprehended, I 15 have illustrated an approved embodiment of the invention in the accompanying drawings and will now proceed to describe the invention in connection with said drawings, in which—

20 Figure 1 represents a view in front elevation, of a sign embodying my invention, Fig. 2, a central, vertical sectional view taken on the plane indicated by the broken line 2—2 of Fig. 1, Fig. 3, a view in elevation of the inside of the back plate of the sign, with the brilliant material secured thereon, and Fig. 4, a view in elevation, of the inside of the front plate of the sign, with the frame around it.

25 Like reference characters indicate the same parts wherever they occur in a plurality of the figures of the drawings.

Referring specifically to the drawings, 30 indicates a suitable frame, such as an ordinary picture frame which is rabbeted or grooved on its inner surface as at 11 to receive the main or face plate 12 of my improved sign, the rabbet or groove being of a greater depth than the thickness of the 35 plate 12 so as to provide a space or pocket to receive the back plate 13 and brilliant material 14.

The back rigid member consists of a plate 40 preferably of wood of the same outside dimensions as the frame 10, said back plate being rabbeted or grooved, around the outer edge of the inside surface, as at 15, so as to leave the inner portion, 16 of approximately one half the thickness of the plate, of exterior 45 dimensions which will admit of its fitting into the rabbet or groove 11 of the frame.

The main or face plate is of glass, or some 50 analogous transparent material which will be rendered opaque throughout all of its extent except those parts as at 17 which are to

be left transparent to permit of the exposure of the brilliant material therethrough, such spaces being in the form of letters, figures or the like.

The parts being constructed as described, 60 the brilliant material 14 is secured as hereinafter described, on the entire area of the inner face of the portion 16 of the back plate, this portion 16 is passed into the pocket of the frame formed by the rabbet, 65 with the brilliant material lying against the inner face of the main plate 12 as in Fig. 1, and showing brilliantly through the clear or transparent spaces in the form of letters, figures, symbols, or the like.

In the sign constructed as described a great 70 variety of material may be used but after much experiment I have produced a brilliant material for this purpose which I consider far superior to any other with which I am acquainted, and find, after full tests, 75 that this material will give a very beautiful, brilliant result which will be lasting, without losing its brilliant appearance.

In the manufacture of my brilliant material, glass is coated with mercury after the manner of Christmas tree ornaments and afterward pulverized, or for some purposes broken very fine, or treated to form very thin scales. Isinglass or mica is likewise 80 mechanically treated by being mashed, broken or otherwise formed into scales. This prepared glass and mica, is mixed with tinsel, or in some instances only one or more of the component parts may be used. The 85 inner face of the back plate 13, hereinbefore described, is coated with a clear, transparent glue, cement, or varnish, upon which the brilliant material is evenly sprinkled or otherwise spread, when suitable pressure is 90 applied to cause all of the component parts of the brilliant material to engage with the cement, glue, or varnish so that none of such material will be wasted off in assembling the 95 parts of the sign together.

The front or face plate of the sign being 100 placed in the pocket or rabbet of the frame, the projecting inner portion of the back plate upon which the brilliant material has been mounted, is pressed into the rabbet of 105 the frame with the brilliant material against the rear face of the face plate or glass, the flange which forms the outer edge of the rear portion of the back plate resting against the back of the frame, covering the 110

rabbet, and where it may be suitably secured by means of glue, cement, nails, screws, or the like.

In a sign of this character, especially wherein a brilliant material is used which forms a multiplicity of facets, it is decidedly advantageous to secure the brilliant material over the entire area of the backing plate, whereby the glass front plate can be changed at any time to show different symbols, and furthermore, by providing a rigid back member for supporting the brilliant material, there is no possibility of the brilliant background folding and creasing as would occur should light flexible material be used, such as paper, fabric or the like. Again, in using the character of brilliant material described, the same is susceptible of collecting dust upon the multiplicity of facets, therefore, to obviate this objection, which would seriously destroy the glitter of the sign, the frame and back plate are provided with rabbets which engage each other and form a practically dust-proof closure.

While I have specifically described the construction of the various component parts of my invention, I desire it to be understood that changes and variations may be made

therein without departing from the spirit and scope of the invention as hereinafter 30 specifically claimed.

Having thus fully described my invention what I claim as new and desire to secure by Letters Patent of the United States is—

A sign, comprising a frame provided with 35 a rabbet in its rear edge, a front-plate having opaque portions and transparent portions forming patterns fitted in said rabbet, and a rigid back-plate also provided with a rabbeted edge forming an inner portion which 40 projects into the rabbet of the frame in close relation to said front-plate and an outer portion which covers the rear side of the frame which surrounds the rabbet, and a coating of finely divided material forming a brilliant reflecting surface fixed to and over the entire area of the inner face of said inner portion of the back-plate and in intimate engagement with said front plate.

In testimony whereof I affix my signature 50 in presence of two witnesses.

CHARLES F. BROADBENT.
